UNITED STATES PATENT OFFICE

SAMUEL SMILEY, JR., OF CINCINNATI, OHIO, ASSIGNOR TO THE GLOBE-WERNICKE COMPANY, OF CINCINNATI, OHIO, A CORPORATION OF OHIO

METAL CABINET

Application filed December 21, 1928. Serial No. 327,686.

This invention relates to filing cabinets or upright cases constructed of metal, and is particularly directed to a cabinet of this nature which is readily assembled and held together without the use of extraneous fastening devices, the interlocking assembly relation of the several parts, making up the cabinet, rigidly fastening and binding the structure together. This type of cabinet is referred to as a "knock-down" cabinet.

More specifically, the invention is concerned with the corner construction of the panels as attachment means for joining the sides, back, and front of the cabinet, in rectangular relation, the front having the visible characteristics of a ladder and providing the respective entrance openings for a series of drawers inserted one above the other in the upright cabinet. The invention concerns, in addition to the above, the arrangement of respective slide elements for supporting the drawers wherein they function to achieve a trussing bracing and binding together of the assembled walls of the cabinet.

It is therefore, an object of this invention to provide a "knock-down" cabinet of strong, durable construction, of which, the several parts may be conveniently packed in flat condition for shipping, and easily and quickly assembled upon delivery.

Another object relates to the edge formation of the respective walls of the cabinet to provide improved interlocking corner constructions for joining the respective side panels, back panel, and front of the cabinet.

Another object is to provide for an assembly of drawer slide elements relative to the ladder or front frame at one end, and in relation to the corner formation of the back at the opposite end, whereby the slide rails function as means for clamping the rear corner connections and as a spreader for rigidly forcing the front frame into interlocking engagement with the formed front edges of the side panels.

Other objects relate to the particular formation and turning of the metal for achieving rigidity of structure, and will be apparent from the foregoing description of the accompanying drawings, in which:

Figure 1 is a perspective view of a cabinet incorporating the present improvements, the cabinet being shown with the drawers removed.

Figure 2 is a perspective view of the ladder frame or front of the cabinet.

Figure 3 is a vertical sectional fragmentary perspective view taken on line 3—3, Figure 1, through the connection of the top to a side of the cabinet.

Figure 4 is a horizontal sectional fragmentary perspective view taken through a rear corner of the cabinet immediately above one of the slide elements, illustrating the manner of connecting the slide element to the back panel of the cabinet for binding the interlocked rear edge of the side in position.

Figure 5 is a horizontal sectional fragmentary perspective view on line 5—5, Figure 1, taken through a forward corner of the cabinet, being through one of the slide elements and showing the engagement of the slide element with the ladder for binding the latter in position.

Figure 6 is a view similar to Figure 5, taken on line 6—6, Figure 1, but varying in that it is taken slightly above the slide element, illustrating the means by which the forward end of the slide element is held down against vertical displacement from a cross piece of the ladder.

Figure 7 is a fragmentary perspective view of a portion of the ladder or front frame showing the connection of a cross piece to the upright thereof.

Figure 8 is a sectional fragmentary perspective view of the lower end of a rear corner of the cabinet taken on line 8—8, Figure 1, illustrating the manner in which the floor of the cabinet is supported relative to the sides.

Figure 9 is a sectional perspective fragmentary view taken on line 9—9, Figure 1, showing the lower end of a forward corner of the cabinet, illustrating the manner in which the floor is supported relative to the lower cross piece of the ladder.

Figure 10 is a sectional view taken on line 10—10, Figure 1, illustrating a drawer slide support in position.

Referring to the drawings, the cabinet as

shown, comprises, upright side panels 10, upright rear panel 11, a front frame or ladder 12, a top 13, a bottom 14, and drawer supporting devices or slide housings 15.

6 Each side panel, as shown in Figures 4 and 5, has opposingly opening channels 16 formed along its vertical edges, these channels formed by turning the respective edge at right angles and then turning back a flange 17 on the right angle portion.

10 The front frame 12 which has the visible characteristics of a ladder, comprises, a pair of upright outwardly facing channel side pieces 18, and a series of downwardly facing channel cross pieces 19, this ladder being detailed in Figures 2 and 7. The cross pieces 19 are secured to the side uprights by the insertion of base web extensions 20 on each end of the cross pieces engaging through slots 21 in the base of the channel iron uprights, the cross pieces being welded to the uprights at the juncture by means of right angle brackets 22. The ladder 12 is engaged into the channels 16 along the respective front edges 25 of the side panels 10, the uprights thereof seating in the respective channels, and the cross pieces being slotted adjacent the uprights as at 23 for interfitting with the inner flanges 17 of the channels 16.

20 30 The rear panel has multi-turned strips 24 secured along its inner vertical margins. These strips interfit and cooperate with the channels along the rear edges of the side panels for securing the back and sides together.

35 The strips, described in detail, comprise, an attaching flange 25 secured along the inner marginal face of the respective side edge of the rear panel, a slot 26 formed by a forwardly extending rectangular portion 40 opening to the rear, a rectangular molding portion 27 disposed outwardly adjacent the slot, and a forwardly extending flange 28 extending from the inner forward corner of the rectangular molding portion. The strips 45 may be attached by welding the flange 25 along the vertical edge of the back. The extreme vertical margin 29 of the back overhangs the rear wall of the molding portion, being spaced therefrom the thickness of the metal.

50 The rear panel may be constructed to include the strips 24 as integral parts thereof since the strips are permanently attached to the panel. The rear panel and strips may be termed a single element of the knock-down cabinet and are shipped permanently fixed together.

55 The molding portion 27 engages within the rear channel of the side panel, the inner flange 17 of the channel being disposed in the slot 26. The side panels are assembled relative to the back by insertion of the channels of the sides through the ends of the slots formed by the strip and back relation and longitudinally sliding the parts together.

60 65 Assemblage of the back panel and side panels

is the first step in the assembly operation. The ladder 12 is then seated in the forward channels of the side panels thus setting up the structure in rectangular relation.

65 70 The slide housings 15 for the drawers to be inserted into the cabinet function as spreader bars to hold the ladder in position and to clamp the rear interlocked connections.

75 Each slide housing is formed of a length of channel iron, additional inner flanges 30 being inwardly turned on the side flanges of the channel. A vertically aligned pair of rivets 31 is provided along the rear margin of each slide housing (see Figure 4), the rivet heads being spaced from the outside of the slide housing permitting the insertion of the rivets in forwardly opening slots 32 in the flange 28 of the retaining strips.

80 85 As shown in Figure 5, an angle piece or clip 33 is secured to the outer or rear side of each slide housing the outwardly extending flange 34 of the angle, being inclined forwardly and adapted to cooperate with the rear flange of the ladder side upright, this flange being inclined inwardly on the same angle as the flange of the angle piece. The slide housings or spreader bars are mounted by inserting the rivets 31 in the respective slots 32 and swinging the housing thereon, bringing the angle piece or spring clip 33 against the acute angled rear flange 34a of the ladder upright until the lower edge of the slide housing engages a respective cross piece of the ladder.

90 95 A device is provided for preventing accidental upward dislodgment of the slide housing or spreader bar, this being in the nature of a protuberance 35 punched outwardly in the web of the ladder upright, the lower edge split from the body to form a tang presenting a sharp edge engaging the lower edge of an aperture 36 formed in the slide housing. (See Figure 6.)

100 105 The top 13 of the cabinet has a rim of double formation. This structure is achieved (see Figure 3) by securing an angle piece 38 to the underside of the cap around its inner side adjacent the integral rim flange 37 of the cap and spaced therefrom, a series of apertures 39 being provided in the downwardly extending flange of the angle piece for cooperation with respective tangs 40 punched inwardly along the top edges of the side panels and back panel and presenting sharp lower edges cooperating with the lower edges of the apertures.

110 115 120 125 The bottom 14 of the cabinet rests along its sides on side angle pieces 41 welded to the respective side panels (see Figures 8 and 9) and at its forward edge is inserted between the top flange 42 of the lower cross piece or apron of the ladder and an offset strip 43 secured to the underside of the top flange. The bottom is assembled prior to the insertion of the slide housings by inserting the 130

front edge thereof as described and forcing the rear portion thereof down onto the angle pieces 41. The bottom edges of the respective sides, back, and front of the cabinet are 5 turned inwardly and upwardly to provide wide base edges 44 for the cabinet.

Having described my invention, I claim:

1. In a metal cabinet, the combination of 10 a rear panel and side panels, the side edges of said rear panel providing vertical slots, which slots extend inwardly from the side edges of the back and thence turn forwardly, and said side panels having inwardly and forwardly turned flanges along their respective 15 rear edges for disposal in the corresponding slots of the back.

2. In a metal cabinet, the combination of 20 a rear panel, side panels, and a front frame removably securing said side panels together, said rear panel having slots along its vertical edges, said slots extending inwardly from the side edges of the back and thence forwardly, and said side panels having inwardly and forwardly turned flanges along their respective 25 rear edges for detachable interlocking engagement in the corresponding slots of the rear panel, and braces wedged between the front of the cabinet and the rear panel for clamping the rear connections together.

3. In a metal cabinet, the combination of 30 opposite upright side panels, a frame joining the front edges of said side panels, and an upright rear panel, said rear panel having formed vertical edges presenting rectangular moldings, each side panel having its respective rear edge turned to provide forwardly facing channels for engagement over the rectangular molding edges of the rear panel, and said rear panel having flanges 35 thereon overhanging the channels for securing the corners in interlocked engagement.

4. In an upright metal cabinet, the combination of opposite side panels, a front frame and a rear panel, said side panels each having 40 rearwardly disposed vertical channels at their front edges, said front frame engaged therein, said rear panel having formed vertical edges presenting rectangular moldings, each side panel having its respective rear edge inwardly turned to provide forwardly facing channels for engagement over the rectangular molding edges of the rear panel, and truss bars extending between the front frame and the rear panel to lock the front frame and 45 rear panel in the respective channels of the side panels.

5. In a metal cabinet, the combination of 50 opposite upright side panels, a front frame, and an upright rear panel, said rear panel having slots formed in its vertical edges, said slots extending inwardly from the sides and forwardly, each of the rear edges of said side panels having formed flanges fitting in a respective slot, said side panels each having 55 rearwardly facing channels formed along its

forward edge, said front frame engaged therein, and bars attached to the back and to the front frame.

6. In a collapsible metal cabinet, the combination of a back, sides, and front, rearwardly facing channels along the front edges of the sides, said front engaging in said channels for securing the sides together, angled slots formed along the side edges of 70 said back, and angled flanges formed along the respective rear edges of said sides for registration with and engagement in said slots, said back having a flange extending forwardly from a wall of each respective slot, and spreader bars attached to the front frame and to the forwardly extending flanges 75 for closing the slots and clamping the side panel flanges therein.

7. A metal cabinet, comprising, in combination, side panels, a rear panel, and a ladder frame, the rear edges of said side panels interlocked with the adjacent side edges of the rear panel, the forward edges of the side panels provided with inwardly extending flanges forming rearwardly opening channels, the 80 uprights of said ladder frame disposed in said channels for securing the forward ends of the side panels together, spreader elements engaging the rear panel toward the side edges thereof, extensions on the forward ends of 85 said spreader elements engaging the rear sides of the ladder frame uprights for holding the ladder frame in position in the channels, and tangs formed on the ladder frame uprights for engagement with said spreader elements to prevent vertical displacement of 90 the forward ends thereof.

8. In an upright metal cabinet, the combination of side panels, a front frame, and a rear panel, said panels and frame secured together in rectangular relation, each vertical edge of said rear panel including a rectangular forwardly extending portion forming a slot opening to the rear of said panel, a squared corner molding portion adjacent the slot and a forwardly disposed support flange extending from the inner forward corner of the squared portion, the rear edges of said side panel provided with forwardly opening channels engaged over the squared corner moldings of the attaching strip, the forwardly extending inner flange of the channel disposed in the slot, and a rear margin of said back panel extending beyond the slot and overlying the rear channel wall.

9. In a metal cabinet, the combination of a rear panel and side panels, the side edges of said rear panel providing slots, these slots extending inwardly from the side edges and thence forwardly, and said side panels having inwardly and forwardly turned flanges along their respective rear edges for disposal in the corresponding slots formed along the side edges of the rear panel.

10. A metal cabinet, comprising, side pan-

- els, a rear panel, and a ladder frame, the rear edges of said side panels interlocked with the adjacent side edges of the rear panel, the forward edges of the side panels provided with inwardly extending flanges forming rearwardly opening channels, the uprights of said ladder frame disposed in said channels for securing the forward ends of the side panels together, spreader bars engaging the rear panel toward the side edges thereof, extensions on the forward ends of said spreader elements engaging the rear side of the ladder uprights for holding the ladder in position in the channels, said engaged rear side of the ladder upright and said extensions on the forward end of said spreader elements inclined slightly forwardly whereby the extension is hooked in position for preventing lateral displacement of the separated bars.
- 10 11. A metal cabinet, comprising, in combination, side panels, a rear panel, and a ladder frame, the rear edges of said side panels interlocked with the adjacent side edges of the rear panel, the forward edges of the side panels provided with inwardly extending flanges forming rearwardly opening channels, the uprights of said ladder frame disposed in said channels for securing the forward ends of the side panels together, spreader elements 20 engaging the rear panel toward the side edges thereof, extensions on the forward ends of said spreader elements engaging the rear sides of the ladder frame uprights for holding the ladder frame in position in the channels, said spreader elements adapted to rest on the respective cross pieces of the ladder frame, and tangs formed on the ladder frame uprights for engagement with said spreader elements to prevent upward displacement of 30 the forward ends thereof.
- 25 35 40

In witness whereof, I hereunto subscribe my name.
